(57) **CLAIM**

The ornamental design for a medical fluid connector, as shown and described.

DESCRIPTION

FIG. 1 is a front view, of which the rear and side views are substantially identical, of a medical fluid connector showing our new design;

FIG. 2 is a top plan view thereof; and,

FIG. 3 is a bottom plan view thereof.

The broken line showing in FIGS. 1 through 3 are for illustrative purposes only and forms no part of the claimed design.
